US00D691779S

(12) **United States Design Patent**
Kim

(10) **Patent No.:** **US D691,779 S**
(45) **Date of Patent:** ** *Oct. 22, 2013

(54) **TIE AND CUFF LINKS RETAIL COMBINATION**

(75) Inventor: **Cin Kim**, Alpine, NJ (US)

(73) Assignee: **Peacock Apparel Group, Inc.**, New York, NY (US)

(*) Notice: This patent is subject to a terminal disclaimer.

(**) Term: **14 Years**

(21) Appl. No.: **29/428,014**

(22) Filed: **Jul. 25, 2012**

(57) **CLAIM**

The ornamental design for a tie and cuff links retail combination, as shown and described.

DESCRIPTION

FIG. 1 is a rear and side perspective view of a tie and cufflinks retail combination showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a first end view thereof; and,

FIG. 7 is a second end view thereof.

The tie hanger and the heads of the cuff links shown in broken lines form no part of the claimed design.

1 Claim, 3 Drawing Sheets
